UNITED STATES PATENT OFFICE.

GUSTAVUS A. HINCKLEY, OF PIT HOLE, PENNSYLVANIA.

IMPROVEMENT IN MECHANISM FOR EFFECTING ROTARY MOTION OF OIL-WELL DRILLS.

Specification forming part of Letters Patent No. 134,889, dated January 14, 1873.

To all whom it may concern:

Be it known that I, GUSTAVUS A. HINCKLEY, of Pit Hole, of the county of Venango, of the State of Pennsylvania, have invented a new and useful Improvement in Mechanism for Effecting Rotary Motion of an Oil-Well Drill, while such may be in operation; and I do hereby declare the same to be fully described in the following specification and represented in the accompanying drawing, of which—

Figure 1 is a top view, and Fig. 2 a side elevation, of a walking-beam and samson-post with my improved mechanism applied thereto.

Such other figures as may be necessary to a proper delineation and description of my invention will be hereinafter referred to.

In a recent application for a patent made by me for a drill roter or rotator I have described as part of one of the elements of combination a peculiar mechanism for operating the pawls or throwing them alternately into and out of action with the crown-wheel.

My present invention is a new and simpler mechanism for such purpose.

In the drawing the walking-beam is shown at A, and its supporting or samson post at B. On the top of the said beam A is the bed-plate C, fixed firmly in place, as shown. The drill-shaft b extends through the walking-beam and carries a pinion, a, the rope x' for suspending the drill being attached to the lower end of the said shaft b. The crown-wheel D, which engages with the pinion a, is shown as arranged on or directly over the bed-plate, and as having on its pivot a lever, c, which has such pivot for its fulcrum, and extends diametrically across the crown-wheel. The two lever-pawls d d' for actuating the crown-wheel are pivoted to the said lever, as shown at e e, and are provided with springs f f to force them toward the said wheel. A long rod, g, hinged to one arm of the lever c, slides freely through a supporting-post, h, and has an arm, i, projecting from it into a slot in a lever, k, pivoted to one side of the walking-beam, and arranged as shown. The lower arm of the lever k is connected with the samson-post by a rod, l, pivoted to an adjustable slide, m', fixed to the post and formed as represented.

From the above it will be seen that when the walking-beam is moved up and down a

reciprocating movement of the pawl-carrying lever c will be produced by means of the slide-rod g, lever k, and rod l.

To the lever c there is applied a mechanism for alternately throwing the pawls into and out of engagement with the crown-wheel, and this mechanism I shall now describe.

Fig. 3 is a transverse section of the bed-plate, the crown-wheel, and the mechanism over the latter.

On the lever c is a slide, E, carrying two projections, m m, extended from it and arranged with the pawls d d', as shown. This slide E is connected to the lever by screws n n going through slots o o in the slide. In rear of the crown-wheel is the ratchet-wheel K with its stud a', the latter during each entire revolution of the ratchet-wheel being moved first against one and next against the other of two projections or cams b' c' extended, as shown, from two levers, q u, arranged over the crown and ratchet wheels and pivoted together and to the bed-plate, the lever q being also pivoted to the slider E, or provided with a stud to enter an elliptical or elongated slot made in such slider at its middle. The retaining-pawl of the ratchet-wheel is shown at z. A lever, L, having the pivot of the ratchet-wheel for its fulcrum, carries a pawl, x, for actuating the ratchet-wheel, such lever L being connected to the lever c by a rod, s, pivoted to the two and arranged as shown. A spring-latch, M, fixed to the bed-plate extends over and upon the lever u, a section of such lever and latch being shown in Fig. 4.

The lever L will have, by means of the connecting-rod s, a reciprocating motion corresponding to that of the lever c, whereby the pawl carried by the lever L will be caused to produce an intermittent rotary motion of the ratchet-wheel, and thereby cause the levers q u to be moved first in one direction and next in the opposite. Such will produce alternate movements of the slide E, whereby each pawl of the rocker-lever under it will, in succession, be thrown out of action upon the crown-wheel, the other pawl at the same time being by its spring forced up to the wheel, so as to cause the said wheel to be revolved by the movement of the lever. The crown-wheel, after being revolved for a time in one direction, will

be turned in the opposite way, such movements being continued so long as the walking-beam may be in operation.

From the above it will be seen that I have dispensed with the racks and toothed sectors used in my former mechanism, and adopted a much simpler construction and arrangement of parts; therefore,

I claim as my present invention—

The lever *c*, the slider *E* with its projections *m m*, the connecting-rod *s*, and lever *L*, ar-

ranged and combined together and with the crown and ratchet wheels *D K* and their actuating-pawl *d d' x*, and also with the levers *q u*, all substantially as described and represented, the said lever *c* being connected with the lever *k* by the rod *g* and its arm *i*, arranged as shown.

GUSTAVUS A. HINCKLEY.
